UNITED STATES PATENT OFFICE.

SAMUEL VAN DERSAL, OF SAN FRANCISCO, CALIFORNIA, ASSIGNOR, BY MESNE ASSIGNMENTS, OF ONE-HALF TO H. L. HATCH, OF SAN FRANCISCO, CALIFORNIA.

COMB.

1,247,908.

Specification of Letters Patent. Patented Nov. 27, 1917.

Application filed January 5, 1917. Serial No. 141,893.

To all whom it may concern:

Be it known that SAMUEL VAN DERSAL, a citizen of the United States, residing at San Francisco, in the county of San Francisco and State of California, has invented certain new and useful Improvements in Combs, of which the following is a specification.

This invention relates to combs and more particularly to an improved device of this character provided with a removable base that enables the space at the bottom of the comb teeth to be readily cleaned.

The principal object of the invention is to provide a cleansable comb which is easily operated, but which at the same time produces effective results.

Another object is to so construct the device that there are no separate parts to become lost, or to be used in the wrong manner.

A still further object of the invention is to embody these features in a device that is neat in appearance and does not differ in looks from the regular combs.

With these and other objects in view, the invention consists of certain novel features of construction, combinations, and arrangements of parts as hereinafter described and more particularly pointed out in the appended claims.

Reference being had to the drawings forming a part of this specification:

Figure 1 is a view in elevation of a comb constructed in accordance with the invention.

Fig. 2 is an enlarged view in section through the same, showing the cleaning strip in position.

Fig. 3 is a view similar to Fig. 2, but with the said strip removed.

Fig. 4 is a view in elevation of one end of a modified form of the device.

Referring to the corresponding parts in the several views by the same numerals of reference, 1 denotes in general a comb having the back 2 and teeth 3, and which is made of any preferred material. Between the teeth are the usual spaces 4, the bottoms 50 of which I prefer to make on an inclination as shown at 5.

Centrally disposed longitudinally of the back 2 is a slot 6, which extends down into

the teeth a short distance as clearly illustrated at 7 in Fig. 3. Denoted by 8 is a strip having the same thickness as the width of the slot 6, and which is adapted to enter this slot and be frictionally held therein. This strip may be of the same material as the comb, or it may be of a contrasting material. For instance if the comb is made of rubber, the strip may be made of metal to secure greater strength, and at the same time if the metal is of a contrasting color, a pleasing ornamental effect is secured. The strip is shaped to the contour of the back of the comb and is pivotally mounted in the slot as shown at 9.

Fig. 4 shows a modified form of the device, wherein the strip 8 is provided with a lug 10 projecting from each side. The comb back has a corresponding recess 11 into which these lugs fit when the strip is in its closed position.

When in use, the dust and lint which in the regular comb is caught in the bottom of the teeth, in this comb gathers on the edge of the strip 8, which I make rounded as shown at 12. Now when it is desired to clean the comb, it is only necessary to remove the strip as shown in Fig. 1. By this operation the matter which accumulates in a matted oily mass in the base of the teeth, is freed from the edge of strip 8 leaving a clean space for a distance equal to the amount the strip extends into the teeth. The clean space thus left enables the bristles of a brush to readily remove the matted material, as they have a chance to get back of the same. In an ordinary comb this material clings so closely to the base that it is very hard to brush out.

In the form shown in Fig. 1, the strip is removed from the slot by first inserting a pin or other thin instrument between the teeth and pushing outwardly on the inner edge of the strip 8, until the latter is moved a sufficient distance to be caught by the fingers. In the form shown in Fig. 4, the strip may be pulled out directly by taking hold of the lugs 10, and these lugs when the strip is closed make a tight fit in the recess 11 so as not to mar the appearance of the article.

While I have shown the preferred form of the invention it will be understood that

changes may be made in minor features of design and construction without departing from the spirit of the invention.

I claim as new and wish to cover by Letters Patent:—

- 5 1. A comb including a back having a longitudinal slot formed therein, and a removable strip pivotally mounted at one end of said slot.
- 10 2. A comb including its teeth and back and having a slot extending longitudinally of said back and partly into said teeth, and a strip in said slot forming a removable base extending into the space between said teeth.
- 15 3. A comb including a back having a slot formed therein, a strip pivotally mounted in one end of said slot, and means formed

on said strip whereby it may be readily removed from said comb.

20 4. A comb including its back and teeth and having a slot formed in the back thereof, and a removable strip pivotally mounted in one end of said slot and extending into the space between said teeth.

25 5. A comb including its teeth and back, inclined faces formed on the inner edge of said back and extending between said teeth, said back having a slot extending longitudinally thereof and into said teeth, and a strip 30 in said slot coöperating with said inclined faces to form a cleansible base.

In testimony whereof I affix my signature.

SAMUEL VAN DERSAL.
